SAFETY RAZOR

Ernest Augustus Brooke, Stockport, England

Application August 2, 1944, Serial No. 547,660
In Great Britain October 28, 1943

7 Claims. (Cl. 30—47)

This invention relates to that kind of safety razor which comprises a blade clamped between a backing plate and a guard plate by means of a handle engaging a screw-threaded post on the backing plate and has for its main object to enable the safety razor to be stored or carried in a more compact form when not in use.

Another object is to provide protection against damage to or cutting by the blade when the safety razor is not in use, without having recourse to the use of a storage case or container.

A safety razor of the hereinbefore specified kind has a two-piece handle the pieces of which are tubular and are disconnectably attached together and provided with longitudinal slits whereby each piece, when detached, can be fitted over the edges of the safety razor and form with the remaining parts of the razor a more compact whole whilst guarding the cutting edges of the blade.

The said pieces are preferably springy so that they grip the safety razor edges when in position thereon.

The outer side of the base plate and/or the guard plate is preferably provided with channels for engagement by one edge of the slit in each piece, so as to increase the security of attachment of the said pieces to the edges of the safety razor.

One of the said pieces may have added to it a knob adapted to be detached and screwed on to the screw-threaded post and thereby guard the screw-threaded post whilst the two pieces are in use as guards.

The said knob may be arranged to hold the said two pieces longitudinally in the guarding position when the knob is screwed on to the screw-threaded post.

I attain these objects by the means herein-after described and shown in the accompanying drawing, wherein—

Figure 1 is a front elevation of a safety razor with its parts assembled for use.

Figure 2 is a side view in medial section thereof.

Figure 3 is a detached cross-section taken on line 3—3 of Figure 1.

Figure 4 is a detached cross-section taken on a line corresponding with line 4—4 of Figure 2.

Figure 5 is a front elevation of the said safety razor with its parts assembled for storage or carry and some of its parts therefore in a different position from that shown in Figures 1 and 2.

Figure 6 is a plan view of Figure 5.

Figure 7 is a side elevation of Figure 5.

Referring to the drawing, in the construction shown therein, as applied by way of example to the well known kind of safety razor comprising a double-edged safety razor blade 1 clamped between a backing plate 2 and a guard plate 3 by the aid of a handle screwed on to a screw-threaded post 4 provided on the backing plate 2 and projecting through apertures in the blade 1 and the guard plate 3, I form the handle tubular in the main and in two parts 5 and 6 respectively, each of a length which is the same as that of the guard plate. The handle may be circular in cross-section as shown, or it may be oval in cross-section.

15 The tubular handle part 5 is provided with an end 7 in which there is a screw-threaded central hole 8 to enable the part 5 to be screwed on to the screw-threaded post 4 in the usual manner. The said part 5 has a longitudinal slit 9 extending 20 from end to end and breaking into the screw-threaded hole. The part 5 is formed at its other end with a portion 10 of externally reduced diameter.

The tubular handle part 6 has a longitudinal 25 slit 11 extending from end to end. The part 6 is formed at one end with a portion 12 of internally increased diameter. At the other end it is formed with a portion 13 of reduced diameter.

A knob 14 has a recess 15 which fits with a 30 tight sliding fit on the portion 13 of the part 6. The knob 14 also has a screw-threaded hole 16 which breaks into the recess 15 and is adapted to be screwed on to the post 4. Externally the knob 14 has a peripheral surface 17 which is 35 concave.

Both tubular handle parts 5 and 6 are of slightly resilient or springy material. In the outer side of the backing plate 2 there are two channels 18 provided at the requisite distance from 40 the side edges thereof and extending from end to end thereof parallel with the side edges. The width of the slits 9 and 11 is normally very slightly less than the total thickness of the guard plate 3, blade 1 and the thickness of the backing plate 2 measured from its inner side to the bottom of the channel 18. Two channels 19 may also be 45 provided in the guard plate 3, the slits 9 and 11 in that case being correspondingly narrower.

In operation, to use the handle, the externally 50 reduced portion 11 of the part 5 is inserted in the internally reduced portion 12 of the part 6 to connect the two parts together and form a handle of convenient length for handling. The knob 14 is placed on the reduced portion 15 to make 55 the handle more comfortable to manipulate.

The handle is then screwed on to the screw-threaded post 4 in the usual manner by means of its end 7 having the screw-threaded hole 8. The parts are then in the position shown in Figures 1 to 4. To store the safety razor in a compact form and guard the edges thereof, the handle is unscrewed from the post 4 and its two parts 5 and 6 are pulled apart. The knob 14 is pulled off the part 6. The part 5 is then slid on to the one edge of the assembled guard plate 3, blade 1 and backing plate 2 from one end thereof so that they enter the slit 9 and one edge of the slit engages one of the channels 18. The other edge of the slit engages one of the channels 19 where provided. The part 5 is slid along the said edge until it completely covers the said edge. The edge of the assembled guard plate 3, blade 1 and backing plate 2 at one side is now situated in the slit 9 and interior of the part 5 which therefore is compactly stored and guards the said edge. Due to the chosen width of the slit 9 and the resiliency of the part 5, the edges of the slit 9 grip the said edge and the part 5 is thereby prevented from accidentally sliding off the said edges. The part 6 is applied to the other edge of the assembled guard plate 3, blade 1 and backing plate 2 in a similar manner. The handle, instead of projecting a considerable distance at an angle as it does in the normal position, lies compactly on the said edges and the safety razor can be conveniently and safely carried in the pocket if desired. The knob 14 is inverted and screwed on to the post in the inverted position by means of its screw-threaded hole 16 so that it forms a guard therefor. When the knob is screwed tight parts of its peripheral surface 17 press externally on the parts 5 and 6 and thereby clamp them and thereby give further security against longitudinal displacement of the parts 5 and 6 on the said edges. The parts are then in the position shown in Figures 5 to 7.

To remove the handle parts 5 and 6 when it is desired to use the safety razor, the parts are slid in reverse direction off the said edges after the knob has been unscrewed from the post 4.

I claim:

1. A safety razor comprising a base plate, a screw-threaded post on the base plate, a guard plate fitting on the said post, a handle part having a longitudinal slit, means on the handle part for screwing it on to the screw-threaded post, a second handle part having a longitudinal slit, and means on the two handle parts for detachably connecting them together, the longitudinal slits being for fitting the two handle parts after disconnection over the edges of the assembled base plate and guard plate when the safety razor is out of use.

2. A safety razor comprising a base plate, a screw-threaded post on the base plate, a guard plate fitting on the said post, a handle part having a longitudinal slit from end to end, a screw-threaded hole at one end of the handle part for screwing on to the said post, an external reduction at the other end of the handle part, a second handle part having a longitudinal slit from

end to end, and an internal enlargement at one end of the second handle part for removably fitting on to the said external reduction, the said slits being for fitting the two handle parts over the edges of the assembled base plate and guard plate when the safety razor is not in use.

3. A safety razor comprising a base plate, a screw-threaded post provided on the base plate, a guard plate fitting on the said post, a handle part of springy material having a longitudinal slit, a second handle part of springy material having a longitudinal slit, means on one of the handle parts for screwing it on to the screw-threaded post, and means on both of the handle parts for detachably connecting them together end to end, the said handle parts forming removable guards for the edges of the safety razor and when in the guarding position gripping the said edges with their slits by virtue of their springiness.

4. A safety razor comprising a base plate, a screw-threaded post on the base plate, a guard plate fitting on the said post, a handle part having a longitudinal slit, means on the handle part for screwing it on to the screw-threaded post, a second handle part having a longitudinal slit, means on the two handle parts for detachably connecting the two handle parts together and channels on the base plate for engagement with the said slits.

5. A safety razor comprising a base plate, a screw-threaded post on the base plate, a guard plate fitting on the said post, a handle part having a longitudinal slit, means on the handle part for screwing it on to the screw-threaded post, a second handle part having a longitudinal slit, means on the two handle parts for detachably connecting them together, and channels in the guard plate for engagement with the said slits.

6. A safety razor comprising a base plate, a screw-threaded post on the base plate, a guard plate fitting on the said post, a handle part having a longitudinal slit, means on the handle part for screwing it on to the screw-threaded post, a second handle part having a longitudinal slit, means on the two handle parts for detachably connecting them together, a removable knob fitting on to the second handle part, and having a screw-threaded hole for screwing it on to the screw-threaded post.

7. A safety razor comprising a base plate, a screw-threaded post on the base plate, a guard plate fitting on the said post, a handle part having a longitudinal slit, means on the handle part for screwing it on to the said post, a second handle part having a longitudinal slit, means for detachably connecting the two handle parts together, a removable knob fitting on the second handle part and having a screw-threaded aperture for screwing it on to the said post, and a surface on the said knob for clamping the handle parts to the safety razor when the said handle parts in a detached state are situated in guarding position on the edges of the safety razor.

ERNEST AUGUSTUS BROOKE.
